(57) CLAIM

I claim the ornamental design for a remote control for gaming, as shown and described.

DESCRIPTION

FIG. 1 is perspective view of a remote control for gaming showing my new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a right side elevational view thereof; and,

FIG. 7 is a left side elevational view thereof.

The broken lines indicate unclaimed portions and form no part of the claimed design.
